PNEUMATIC DRILL

Harvey B. Rodstein, 6419 Shenandoah Ave.,
Los Angeles, Calif. 90056

Filed June 11, 1969, Ser. No. 17,651

Term of patent 14 years

Int. Cl. D8—02

U.S. Cl. D8—68

FIG. 1 is a perspective view of my pneumatic drill;
FIG. 2 is a side elevational view thereof;
FIG. 3 is a top view thereof;
FIG. 4 is a rear end view thereof;
FIG. 5 is a front end view thereof; and
FIG. 6 is a bottom view thereof.

I claim:

The ornamental design for a pneumatic drill, substantially as shown and described.
